UNITED STATES PATENT OFFICE.

WALTER F. ZICK, OF ALHAMBRA, CALIFORNIA.

GAS HEATING STOVE.

Application filed July 5, 1927. Serial No. 203,434.

My invention relates to a stove for burning the ordinary fuel gas for heating purposes and the object thereof is to provide a stove which will produce a maximum amount of heat for gas consumed and which will prevent the formation of objectionable odors.

In the drawings forming a part of this application Fig. 1 is a front elevation of my improved stove. Fig. 2 is an enlarged section on the line 2—2 of Fig. 5. Fig. 3 is an enlarged sectional detail of a portion of one end. Fig. 4 is a top plan of the base member and burner. Fig. 5 is a back elevation.

Referring to the drawings the base member 5 is the shape of an elongated pan formed of sheet metal with parallel sides and ends and with the bottom 6 uppermost as best shown in Fig. 2. On the corners of 5 are secured legs or feet 7 by bolts 8. The outer casing is of sheet metal and is composed of narrow vertical corner portions 9, end portions 10 and back portion 11. Narrow horizontal finishing strips 12 at the top and 13 at the bottom extend across the front. In the end walls are end linings 14 which are provided with guide grooves 15 and 16 which are further apart at the bottom than at the top. Grooves 15 are adjacent to the front and in them is received a reticulated member 17 which is covered with asbestos wool. In grooves 16 is received a sheet metal member 18, the face of which adjacent member 17 is covered with asbestos wool 19. The top of member 18 is bent toward member 17 and covers the space therebetween as shown in Fig. 2. A gas burner 20 extends along the base of member 18 and projects through the lining and one end and has a regulating cock 21 thereon. Burner 20 is of an approved construction. Just within the front members is a wire netting 22. A cover 23 completes the stove. Cover 23 is of sheet metal and has rounded edges which spring over the out turned top edges of the outer casing and is held thereon by friction. Ornamental corner tips 24 may be secured to the cover. Members 6—14—15 and 18 form a combustion chamber with a reticulated front, the front and back walls of which are closer at the top than at the bottom and all of the products of combustion are compelled to pass through the reticulated front which soon becomes highly heated thereby insuring perfect combustion

and preventing the formation of any objectionable odors. The back wall of the outer casing may have a draft or vent port 25 which would be formed by punching in a portion thereof. In the end wall adjacent to cock 21 is a lighting port 26 into which a lighted match may be inserted when the burner is to be lighted. In member 5 adjacent to burner 20 are air ports 27 through which air passes to aid combustion. By the formation of a combustion chamber with a reticulated front and the use of a wire netting in front thereof there is no flare back when lighting the gas. The use of the reticulated front and wire netting prevents the ignition of clothing from the flame of the burner. By this construction the products of combustion pass out of the reticulated front over the combustion chamber and down and out of the port in the back of the casing, thereby utilizing to the greatest extent the heat units of the fuel.

Having described my invention I claim—

1. A heating gas stove comprising an outer casing composed of sheet metal walls except the front wall, said front wall being partly of sheet metal and partly of wire netting, the back wall having a port therein; a combustion chamber within said casing attached to the bottom wall of the casing and spaced from the back and front walls, said combustion chamber having imperforate back and end and top walls with the front surface of the back portion covered with asbestos wool; a front wall of said combustion chamber being reticulated and covered with asbestos which does not close the openings, the front and back walls of said combustion chamber being spaced further apart at the bottom than at the top; and a burner in said combustion chamber.

2. A gas heating stove comprising a casing formed of an imperforate top, and end and bottom walls and a back wall with a port therein and a front wall of wire netting reenforced at the top and sides with strips of metal, said casing being in horizontal section a parallelogram and having a lighting port in an end wall and air ports in the bottom wall, means to support said casing elevated; a combustion chamber mounted on the bottom wall of said casing having the reticulated front wall spaced from the back wall further at the bottom than at the top, the other walls of said combustion chamber being imperforate; and a burner along the

bottom wall within the combustion chamber.

3. In a gas heating stove the combination of an outer sheet metal casing having a wire net front, and having ports in the bottom 5 wall and a lighting port in an end wall; with a combustion chamber mounted on the bottom wall and having imperforate back, top and end walls and a reticulated front wall.
- 10 4. In a gas heating stove the combination of an outer casing; with a combustion chamber

mounted on the bottom wall of said casing of less height than the casing, the back and front walls of said combustion chamber being spaced further apart at the bottom 15 than at the top, the front walls of said casing and chamber being reticulated and a burner at the bottom of said combustion chamber.

In witness that I claim the foregoing I have hereunto subscribed my name this 25th 20 day of June, 1927.

WALTER F. ZICK.
